UNITED STATES PATENT OFFICE

140,207

DESIGN FOR AN AIRPLANE

Kenneth L. Bunyard, Flushing, N. Y.

Application February 26, 1944, Serial No. 112,723

Term of patent 14 years

(Cl. D71—1)

To all whom it may concern:

Be it known that I, Kenneth L. Bunyard, residing at Flushing, in the county of Queens and State of New York, a citizen of the United States, have invented a new, original, and ornamental Design for an Airplane, of which the following is a specification, reference being had to the accompanying drawings, forming a part thereof.

Fig. 1 is a top or plan view of an airplane showing my new design;

Fig. 2 is a view in front elevation;

Fig. 3 is a view in side elevation with landing gear up and in a cruising attitude;

Fig. 4 is a view in rear elevation; and

Fig. 5 is a view comparable to Fig. 3 but with the landing gear down and showing the attitude of the plane when restng on the ground.

I claim:

The ornamental design for an airplane, as shown.

KENNETH L. BUNYARD.
